(57) **CLAIM**

The ornamental design for a tire, as shown and described.

DESCRIPTION

FIG. 1 is a perspective view of the tire.

FIG. 2 is a perspective view of the tire.

FIG. 3 is a side view of the tire; and,

FIG. 4 is a front view of the tire.

In the drawings, the broken lines defining the hub, sidewall, inner bead depict environmental subject matter that forms no part of the claimed design.
